CLAIM

The ornamental design for a tablet stand with ball joint, as shown and described.

DESCRIPTION

FIG. 1 is an isometric front view of a tablet stand with ball joint showing the new design;

FIG. 2 is a front view of the design of FIG. 1;

FIG. 3 is a right side view of the design of FIG. 1;

FIG. 4 is a left side view of the design of FIG. 1;

FIG. 5 is a top view of the design of FIG. 1;

FIG. 6 is a bottom view of the design of FIG. 1;

FIG. 7 is a back view of the design of FIG. 1;

FIG. 8 is an isometric back view of the design of FIG. 1;

FIG. 9 is an isometric front view of the design of FIG. 1 showing a tablet as additional environment;

FIG. 10 is an isometric front view of a tablet stand with ball joint showing a first alternative embodiment of the new design;

FIG. 11 is a front view of the design of FIG. 10;

FIG. 12 is a right side view of the design of FIG. 10;

FIG. 13 is a left side view of the design of FIG. 10;

FIG. 14 is a top view of the design of FIG. 10;

FIG. 15 is a bottom view of the design of FIG. 10;

FIG. 16 is a back view of the design of FIG. 10; and,

FIG. 17 is an isometric back view of the design of FIG. 10.

The broken lines showing selected portions of the tablet stand with ball joint and the tablet in FIG. 9, is for environmental purposes only and forms no part of the claimed design.
